UNITED STATES PATENT OFFICE.

JAMES P. SHARP, OF SALT LAKE CITY, UTAH.

BRAKING DEVICE FOR SLEDS.

1,185,137.

Specification of Letters Patent. Patented May 30, 1916.

Application filed February 13, 1915. Serial No. 8,093.

To all whom it may concern:

Be it known that I, JAMES P. SHARP, a citizen of the United States, and a resident of Salt Lake City, in the county of Salt Lake and the State of Utah, have invented 5 certain new and useful Improvements in Braking Devices for Sleds, of which the following, together with the accompanying drawings, constitutes a full, clear, and exact 10 specification, which will enable others skilled in the art to which my invention appertains to make and use the same.

My invention relates to braking devices for sleds and its object is to provide means 15 for easily dropping one or more suitable bands or bracelets under the sled runners after the manner of a so-called "rough lock." While my device is intended to be used primarily in connection with coasting sleds in 20 cases of emergency, yet its use is not restricted thereto.

The features upon which I desire protection are summarized in the appended claims.

In the drawings, which illustrate merely 25 one embodiment of my invention, Figure 1, is a perspective view of a common sled showing my improvement applied thereto, a portion of the steering bar being broken away to show a detail more clearly. Fig. 2 30 is a partial, enlarged side elevation of the same, and Fig. 3 is a fragmentary perspective view of a modified detail.

Referring to the drawings (3) represents 35 an ordinary coasting sled, and (4) the runners thereof, on which are strung the encircling bands or bracelets (5), these being preferably made of metal and having any suitable form, though if made of one piece of metal it may be desirable to have what 40 is commonly known as an "open link" for the sake of easy application to the runners.

Normally the bracelets (5) hang high up on the front of the runners, in order not 45 to interfere with the operation of the sled, and they are held in this position by the bent fingers (6) which project from the rod (7), the latter being pivoted at (8) in the framework of the sled.

Instead of pivoting the rod (7) directly in 50 the framework as shown in Figs. 1 and 2 it may be hung in removable clips or stirrups (8^a) as shown in Fig. 3, these stirrups being clamped to the framework by a bolt (8^b). The form of the stirrups (8^a) 55 and the method of attaching them may be varied to suit any special requirements.

The fingers (6) are adapted to allow their lower extremities to bear against the inner surfaces of the runners (4) and are held in yielding contact thereon, preferably by the 60 springs (9), as shown. The pivoted rod (7) carries the rigidly attached operating lever (10) which latter may terminate in the ball (11) for the purpose of being conveniently grasped by the hand, or touched 65 by the foot, of the operator.

In using my device, the lever (10) is pushed over sufficiently far, as indicated by dotted lines, so, as to allow the bracelets (5) to slide down along the runners by gravity. 70 The bracelets (5) on touching the surface (as shown by the dotted lines at (5^a) in Fig. 2) on which the sled is sliding, are soon worked back along the runners until they catch on the forward standards of the sled 75 and finally lodge in the positions shown approximately by the dotted lines (5^b) in Fig. 1, thereby retarding the motion of the sled and quickly bringing the same to a stop.

Having fully described my invention, 80 what I claim is:

1. The combination, with the framework and the runners of a sled, of arms pivoted in the said framework and adapted to have their free ends touch the said runners; means 85 for normally holding the arms in yielding contact with the runners; and bracelets, independent of the said arms, loosely encircling the said runners, the said arms being adapted to normally support the said bracelets in predetermined positions on the said runners.

2. In a sled, the combination with the framework and the runners thereof, of pivoted arms adapted to have their free ends 95 bear against the said runners, means for normally holding the free ends of the said arms against the runners, and bracelets, independent of the said arms, movably strung on the said runners, the said arms being adapted to support the bracelets on the said runners at certain predetermined points, and means for releasing the said bracelets at the will of the operator.

3. In a sled having upwardly curved runners, the combination therewith of independent bracelets loosely strung on the curved portions of the said runners; and suitably disposed arms for normally holding the said bracelets high up on the said curved portions, the said arms being adapted to allow the release of the said bracelets, and the lat-

ter being adapted to thereupon gravitate downwardly along the said curved portions of the runners for the purpose specified.

4. In a braking device for sleds having runners the combination with the sled framework, of removable clips suitably fastened thereto, a rod pivoted in the said clips, fingers projecting from the said rod, the said fingers being adapted to contact the runners of the sled, and bracelets loosely strung on the said runners, the said fingers being adapted to support the said bracelets on portions of the said runners not in contact with the surface on which the sled is being used, and means for moving the said rod and its fingers at the will of the operator for the purpose specified.
5. The combination with the framework

and the runners of a sled, of stirrups removably attached to the said framework, arms pivoted in the said stirrups and adapted to have their free ends touch the said runners, means for normally holding the arms in yielding contact with the runners; and bracelets, independent of the said arms, loosely encircling the said runners, the said arms being adapted to releasably support the said bracelets in predetermined positions on the said runners for the purpose specified.

In testimony that I claim this invention as my own, I have signed this specification in the presence of two subscribing witnesses.

JAMES P. SHARP.
